DESIGN FOR A PHOTOGRAPHER'S FILM MAGAZINE LOADING TOOL OR SIMILAR ARTICLE

Henry G. King, Lorain, Ohio

Application October 7, 1939, Serial No. 87,570

Term of patent 14 years

To all whom it may concern:

Be it known that I, Henry G. King, a citizen of the United States, residing at Lorain, in the county of Lorain and State of Ohio, have invented a new, original, and ornamental Design for a Photographer's Film Magazine Loading Tool or Similar Article, of which the following is a specification, reference being had to the accompanying drawing, forming a part thereof, in which:

Figure 1 is a perspective view of a photographer's film magazine loading tool or similar article, showing my new design; and

Figure 2 is an end elevational view taken from the upper end of Figure 1.

I claim:

The ornamental design for a photographer's film magazine loading tool or similar article, substantially as shown.

HENRY G. KING.
